UNITED STATES PATENT OFFICE.

CHARLES GAEBLER, OF POUGHKEEPSIE, NEW YORK.

HOT-WATER BOILER.

SPECIFICATION forming part of Letters Patent No. 760,734, dated May 24, 1904.

Application filed February 27, 1904. Serial No. 195,654. (No model.)

To all whom it may concern:

Be it known that I, CHARLES GAEBLER, a citizen of the United States, residing at Poughkeepsie, in the county of Dutchess and State of New York, have invented certain new and useful Improvements in Hot-Water Boilers, of which the following is a specification.

My invention relates to improvements in hot-water boilers, and has for its purpose the construction of a boiler in such a manner as to obtain a minimum of space in the installation thereof, together with the greatest heating effects upon the water to be circulated from the boiler to a building or by means of a system of pipes or by any other well-known method of building-heating.

The special objects of this present invention are to so arrange the fire-box as to produce the greatest heat area upon the water-pipes, to provide a means for conducting off gases from a fire-box without in any way interfering with the extent of the space for the water-pipes or boiler portion, and to arrange the flow-pipes in the best manner possible for establishment of a flow from and return to the boiler. These objects are obtained by a specific structure and arrangement of parts which will appear hereinafter and be fully described, as well as illustrated in the accompanying drawings, in which—

Figure 1 is a section taken central of the boiler and furnace. Fig. 2 is a plan view of the top of the boiler.

Referring more particularly to the drawings, A represents the main body of the furnace, within the cavity B of which is arranged the boiler C and the fire-box D. This fire-box D is located at the lower end of the cavity B of the furnace-body A and comprises the vertical walls d and the grate d'. Below this grate is an ash-pit E. Surrounding the vertical walls of the fire-box is a water-leg F, which is formed integral with the walls d of the fire-box and has in communication with the lower portion thereof a pair of return-pipes G, these pipes extending through the walls of the furnace-body and serving the usual purpose of return-pipes. Arranged within the fire-box, which is in open communication with the cavity B of the furnace-

body, there is disposed the heating-boiler C. This boiler comprises a water-leg H, arranged at its lowermost portion, which has a series of short pipes h, being four in number in this structure, which connect this boiler-leg H with the upper portion of the water-leg F surrounding the fire-box, whereby a communication is formed between the said water-leg F and the water-leg H of the boiler. The furnace-opening b is enlarged around this portion of the boiler, so that gases may flow entirely around as well as upwardly through the leg H, which is formed with a central opening through the same. This arrangement gives a large heating area within a portion of the boiler and to the pipes thereof. Arranged in a double line around this water-leg H there are a series of water-pipes I, which are in communication with the water-leg at their lower extremity and which project vertically upward toward the upper end of the furnace-cavity. At their upper extremity they are in communication with the second and main water-leg J, which is composed of walls forming the chamber, extending entirely around the boiler, between which walls and central thereof there is an opening which is disposed vertically above the central opening of the lower water-leg. The furnace-opening B is contracted between these water-legs H and J, so as to come into contact with the pipes I, as seen at b, while just above this projection B the furnace-opening again enlarges, leaving a space around the water-leg J of a substantial oven shape, wherein is gathered the products of combustion from the fire-box, these being led off through a smoke-flue K. Leading off from the water-leg J are flow-pipes L, from which the water or steam is conducted throughout a building and on the return of the water by means of a system of pipes (not shown, but readily understood in their use) is led to the return-pipes G, above mentioned. Upon the flow-pipes L are secured auxiliary flow-pipes M, which lead vertically upwardly to another system of pipes for the purpose of circulating the heating medium.

Upon reference to Fig. 2 it is seen that the upper portion of the water-leg J is provided with flanges J', which are formed on the for-

ward and rear face of this water-jacket and water-leg and engage in the walls of the furnace-body for the purpose of lending a supporting means to the body of the boiler and also for securely retaining the boiler in position.

It is seen from the foregoing description that this furnace has been so constructed as to economize space, to require a simple number of parts, and at the same time to secure the full benefit of the combustion in the firebox. It is these advantageous results due to the specific structure of the present invention which I wish to protect myself upon. Many slight changes and variations may be introduced; but I believe that I am entitled to cover the same in this application, as mere changes in detail of structure are fully contemplated and believed to lie within the scope of the present invention.

What I claim, therefore, and desire to secure by Letters Patent of the United States, is—

1. In a heating apparatus of the type set forth, the combination with a furnace-body having enlarged upper and lower chambers and a contracted portion within the same, a fire-box disposed at the lower portion of the lower chamber having a water-leg surrounding the same, return-pipes communicating with the lower portion of the water-leg, a boiler arranged within the upper and lower chamber, said boiler comprising an upper and lower water-leg having central openings there-in forming a smoke-flue, a series of water-pipes connecting the lower water-leg of the boiler with the water-leg surrounding the fire-

box, and flow-pipes leading off from the upper water-leg, substantially as described.

2. In a water-heating apparatus, the combination with a furnace having a cavity therein being enlarged at the top and bottom portions and contracted centrally, of a boiler comprising a fire-box located at the bottom portion of the furnace-cavity, a water-leg surrounding and integral with the fire-box having return-pipes in communication therewith, vertically-disposed pipes leading from the upper end of the water-leg, a lower water-leg forming a portion of the boiler having communication with said pipes, a series of pipes arranged in a double row upon the water-leg of the boiler, said pipes lying within the contracted portion of the furnace-cavity, an upper water-leg disposed at the upper portion of said series of pipes lying within the upper and enlarged chamber of the furnace-cavity, flanges formed integral therewith extending outwardly from the forward and rear face thereof adapted to engage in the furnace-body for supporting the boiler, flow-pipes communicating with the upper water-leg of the boiler, and a smoke-flue adapted to carry products of combustion, said products circulating centrally upwardly through the boiler and adapted to flow around the pipes of the boiler, substantially as set forth.

In testimony whereof I have signed my name to this specification in presence of two witnesses.

CHARLES GAEBLER.
